UNITED STATES PATENT OFFICE

FREDERICK A. HOLT, OF ARLINGTON, NEW JERSEY, ASSIGNOR TO JEWEL TOOL SPECIALTY COMPANY, OF NEW YORK, N. Y., A CORPORATION OF NEW YORK.

SCREWDRIVER.

1,355,743.

Specification of Letters Patent.

Patented Oct. 12, 1920.

Application filed October 28, 1919. Serial No. 333,911.

To all whom it may concern:

Be it known that I, FREDERICK A. HOLT, a citizen of the United States, and a resident of Arlington, in the county of Hudson and 5 State of New Jersey, have invented a new and Improved Screwdriver, of which the following is a full, clear, and exact description.

This invention relates to improvements 10 in screwdrivers, an object of the invention being to provide improved means for connecting the tool with the handle.

A further object is to provide with a tool, 15 a tool holding pin which also functions as a means for holding the tool receiving nipple against rotary movement in the handle.

A further object is to provide a screwdriver of extremely simple construction which will insure a strong and rigid connection 20 between the handle and the tool and which will permit the ready removal of the tool notwithstanding the strain and stresses which may be put upon the same, and which will tend to bind the tool in the handle.

25 With these and other objects in view the invention consists in certain novel features of construction, and combinations and arrangements of parts, as will be more fully hereinafter described and pointed out in the 30 claims.

In the accompanying drawings—

Figure 1 is a view in longitudinal section illustrating my improvements;

Fig. 2 is a view in cross-section on the line 35 2—2 of Fig. 1;

Fig. 3 is a view in elevation of one of the nipples removed; and

Fig. 4 is a perspective view of the screwdriver 5.

40 1 represents a cylindrical metal handle preferably having a milled or roughened surface and 2 and 3 represent metal nipples which are located in the ends of the handle and operate to receive the shanks 4 of tools 45 5. While I shall hereinafter refer to the tool 5 as a screwdriver, it is obvious that the structure may be utilized for supporting and operating other forms of tool and I do not wish to be limited to screwdriver tools, 50 although it is the primary purpose of my device.

The nipple 2 at its outer end is of approximately the same external diameter as the handle 1, but at its inner end is in the form 55 of a tubular projection 6 which snugly fits

in the bore of the handle 1. A pin 7 is projected through an opening 8 in the nipple 2 and is located at an angle to the longitudinal axis of the nipple and handle. In other words, the hole 8 is bored or formed 60 in the nipple at an incline or angle so that the inner end of the pin is at an incline or angle and presents a beveled or sloping surface to receive thereagainst the beveled or sloping surface 9 of shank 4 of the tool 5. 65

This shank 9 is curved in cross-section constituting approximately half of a cylinder with a flat inclined surface forming a wedge which, when moved into position against the end of the pin 7, exerts a wedging action to 70 hold the shank in the handle. As the pin 7 is relatively of small diameter, a relatively small friction surface is presented to the inclined face 9 of the shank and while a wedging action is had, there is no extensive frictional engagement as would be the case if a relatively long wedge were provided in the handle. This is important as it is, of course, desirable to remove the tool from 75 the handle from time to time and while the pin serves to hold the shank, it does not prevent the removal of the tool because of the fact that its surface contact with the shank is relatively limited.

The shank 4 of the tool 5 is of slightly 80 smaller diameter than the main portion of the tool so as to provide an annular shoulder 13, and the nipple 2 has a counterbore 10 at its outer end receiving the tool 5 and providing a shoulder 11 which limits the inward movement of the shoulder 13. These 85 shoulders 13 and 11 prevent any possibility of the tool being forced into the handle sufficiently far to prevent removal of the tool, and furthermore, the counterbore 10 90 receiving the tool 5 gives a stronger bearing surface for the handle on the tool. 95

As above stated, the pin 7 is positioned in the nipple at an angle to the longitudinal axis thereof and by reason of such position 100 the outer end at one side of the pin will extend beyond the outer surface of the tubular projection 6 so that when the nipple is forced into the handle, the projected end of the pin operates as a key to cut its way into 105 the inner surface of the handle as shown somewhat exaggerated by the reference numeral 12. The pin therefore not only operates as a holding means for the shank of the tool, but also secures the nipple in the 110

handle so as to prevent possibility of independent rotary movement of the nipple.

I have illustrated nipples 2 and 3 at the respective ends of the handle as it is desirable sometimes to so construct the handle as to accommodate smaller sized shanks in one end than in the other, thus enlarging the use of the handle. The nipple 3 is precisely like the nipple 2 except that the counterbore 10 is dispensed with to illustrate the fact that the nipple may have this counterbore or not, as desired.

Various slight changes may be made in the general form and arrangement of parts 15 described without departing from the invention, and hence I do not limit myself to the precise details set forth but consider myself at liberty to make such changes and alterations as fairly fall within the spirit 20 and scope of the appended claims.

I claim:

1. A device of the character stated, comprising a handle, a tubular nipple in the handle, a pin located in the wall of the nipple 25 and positioned at an angle to the longitudinal axis of the nipple, a tool, and a shank on the tool having an inclined face adapted to engage the inner end of the pin, said pin at its outer end at one portion 30 thereof projecting beyond the surface of the nipple and having locking engagement with the inner face of the handle.

2. A device of the character stated, comprising a cylindrical metal handle, a nipple

having its outer portion of approximately 35 the same diameter as the handle and having a tubular projection fitting within the handle, said tubular projection having an opening in its wall, a pin secured in said opening and located at an angle to the longitudinal 40 axis of the nipple, the outer edge of said pin adapted when the nipple is moved into the handle to cut into the inner surface of the handle and hold the nipple against rotary movement in the handle, a tool, and a shank 45 on the tool having a beveled wedge-shaped inner portion adapted to engage the inner end of the pin.

3. A device of the character stated, comprising a cylindrical metal handle, a nipple 50 having its outer portion of approximately the same diameter as the handle and having a tubular projection fitting within the handle, said tubular projection having an opening in its wall, a pin secured in said opening 55 and located at an angle to the longitudinal axis of the nipple, the outer edge of said pin adapted when the nipple is moved into the handle to cut into the inner surface of the handle and hold the nipple against rotary 60 movement in the handle, a tool, and a shank on the tool having a beveled wedge-shaped inner portion adapted to engage the inner end of the pin, said nipple and tool having annular shoulders limiting the inward 65 movement of the tool in the handle.

FREDERICK A. HOLT.
